US00D485294S

(12) **United States Design Patent** (10) Patent No.: **US D485,294 S**
 Albert (45) Date of Patent: ** Jan. 13, 2004

- (54) **ELECTRODE STRUCTURE FOR AN ELECTRONIC DISPLAY**
- (75) Inventor: **Jonathan D. Albert**, Cambridge, MA (US)
- (73) Assignee: **E Ink Corporation**, Cambridge, MA (US)
- (**) Term: **14 Years**
- (21) Appl. No.: **29/162,884**
- (22) Filed: **Jun. 20, 2002**

Related U.S. Application Data

- (63) Continuation of application No. 09/359,937, filed on Jul. 22, 1999.
- (60) Provisional application No. 60/093,689, filed on Jul. 22, 1998.
- (51) **LOC (7) Cl.** **18-03**
- (52) **U.S. Cl.** **D18/26**
- (58) **Field of Search** D18/26; D13/121; 340/7.55; 40/447, 450, 451; 345/55, 56, 59

FOREIGN PATENT DOCUMENTS

- EP 0 180 685 5/1986

Primary Examiner—Charles A. Rademaker

(74) *Attorney, Agent, or Firm*—Testa, Hurwitz & Thibeault, LLP

(57) **CLAIM**

The ornamental design for an electrode structure for an electronic display, as shown and described.

DESCRIPTION

FIG. 1 is a plan view of an electrode structure for an electronic display showing my new design; and,

FIG. 2 is a modified embodiment of the design shown in FIG. 1.

The claimed design is of no substantial thickness.

The sides opposite FIGS. 1 and 2 are mirror images thereof.

UNITED STATES PATENT AND TRADEMARK OFFICE
CERTIFICATE OF CORRECTION

PATENT NO. : Des. 485,294 S
DATED : January 13, 2004
INVENTOR(S) : Albert

Page 2 of 4

It is certified that error appears in the above-identified patent and that said Letters Patent is hereby corrected as shown below:
